UNITED STATES PATENT OFFICE.

GEORGE YULE, OF NEWARK, NEW JERSEY.

DYE-TUB.

SPECIFICATION forming part of Letters Patent No. 244,509, dated July 19, 1881.

Application filed May 6, 1880. (No model.)

To all whom it may concern:

Be it known that I, GEORGE YULE, of the city of Newark, in the county of Essex and State of New Jersey, have invented a new and 5 useful Improvement in Dye-Tubs, of which the following is a description.

My invention relates to an improvement in dye-tubs, and relates especially to those heated by steam and employed in dyeing hats; and 10 it consists, first, in providing the soft wood-work of the dye-tub with a metallic sleeve, where the connection is made to the coil in the interior, said sleeve being permanently secured in the wood and connected with the coil by 15 any suitable coupling, so as to be attached and detached at pleasure without breaking any joint in the tender wood; second, in providing a false bottom with a central wooden post, whereby the bottom may be permanently connected with the hoisting apparatus without interfering with the continued use of the tub, the wooden post being free from corrosion by 20 the dye-liquors, and its central position enabling the contents of the tub to be reached 25 and stirred without hinderance; third, in providing the false bottom with a border or guard of flexible material at its margin to prevent the goods being jammed into the crevice at that point; and, fourth, in the employment of 30 a packing around the edge of the false bottom to prevent the articles being jammed into the crevice at that point.

My invention is designed to obviate the difficulties encountered in the use of the tubs now 35 in common use, wherein the coil at the bottom becomes clogged or covered with dye-stuffs, thereby preventing the desired radiation of the heat. The tubs in common use are also made square, whereby the convenient stirring and 40 movement of the goods in the liquor are prevented, and the appliances for lifting out the bottom, being connected with the same at the sides, interfere greatly with the stirring of the goods, as desired, and convenient access to all 45 sides of the vessel.

Figure 1 of the drawings is a sectional elevation at the center of my improved dye-tub; Fig. 2, a front view of the hoisting-crab; Fig. 3, a plan of the coil in the tub; Fig. 4, a plan 50 of the false bottom; Fig. 5, an enlarged sec-

tional view of the false bottom and its lifting-post, and Fig. 6 an enlarged sectional view of the sleeve and union for the coil-joint.

To facilitate the stirring of the contents I make my tub A round and provide the false 55 bottom B with a central post, R, to which is attached the rod or chain C, connected with the barrel b of the hoisting-crab. The latter is secured to the adjoining wall or any convenient fixture, and the rope carried thereto over pulleys E fixed overhead. The hoisting-crab is formed with a worm-gear, g, attached to the barrel b, and a worm, w, meshing into the gear and turned at pleasure by a crank, c. Great 60 power is thus secured to lift the bottom B and its load of goods at any time, and the worm forms a self-locking device to prevent the barrel from running backward at any time. It also serves to hold the bottom at any desired 65 height in the tub, without the aid of other fixtures for that purpose. The entire space around the post R is free from obstruction to the stirring of the goods in the liquor, and the whole margin of the tub is equally free from obstructions without and within. The post is preferably 70 made of wood to withstand the dyes employed; and I construct the same with an iron rod, I, through the middle, and form the rod with a head, i, at the bottom, resting against an iron washer, u, beneath the center of the 75 false bottom. I also apply a lead cap, a, to the bottom B, over the head i and washer u, to protect them from the dye-liquor, securing the same by brass nails or screws, or otherwise. An eye, e, is provided at the top of the rod I 80 to attach the chain or rope C.

If preferred, the eye e may be attached to the top of the post by the cast-iron cap e', and the post be secured to the bottom B by three or four bolts, with their nuts concealed in the 85 wood of the post, and the heads covered by a lead plate, a, as described above. In such case the cap e' would be secured to the top of post B by bolts in any convenient manner, as they are above the action of the dye-liquor in 90 the tub.

In Fig. 1 is shown a rope, r, attached to the edge of the false bottom by screws and bearing snugly against the sides of the tub to prevent the jamming of the goods at that point. 95

A hollow hose may be used instead of the rope, or any suitable material having the requisite flexibility and firmness combined.

By lifting out the false bottom the coil *d* is exposed, and to permit the ready removal of the same to be repaired, or for cleaning the tub when clogged, I form the coil with joints inside the tub, instead of extending the ends through the side or bottom to connect with the feeding steam-pipe.

To secure a joint inside, and form a connection with the feeding steam-pipe *f*, I fit two sleeves, *h*, through the side of the tub and make each tight in its place by a collar inside and a nut outside, as at *m n*. The outer end of the sleeve is screwed to fit the steam-pipe or its coupling, and the inner end is fitted to a union, *o*, applied to the end of the heating-pipe. One sleeve thus serves as an inlet for supplying steam to the coil, and the other as an outlet to drain away the condensed water. By this arrangement a damaged coil can be removed and another replaced in a few minutes without breaking any joints made in the tender wood-work, as is now customary.

The false bottom is shown in the drawings as made of two series of wooden slats crossed upon one another; but my invention has no reference to any particular construction of bottom, and is applicable to any false bottom applied in a tub for the purpose described, and the construction of the union-joints may be modified as desired, without affecting the essential feature of the improvement I have made in attaching the coil to the tub. This consists in fitting the sleeves *h* permanently into the wood of the dye-tub, so that the coil can be removed by a screw-coupling or union within the tub, and all damage to the wood of the tub be avoided, as well as the delay of breaking and packing a joint in the wood every time the coil is removed and replaced. The wooden post *R* may also be used without any central rod, *I*, as the essential feature of the post is its being externally of wood, so as to be little affected by the dyeing-liquids, and its function is merely to lift the false bottom without interfering with the use of the tub in any re-

spect, the combination of the central post with a round tub affording the utmost facility for stirring and reaching the contents.

I am aware that removable false bottoms are not new, and that they have been provided with lifting devices to elevate them from the tub for the removal of the stock when dyed; but such lifting devices have not been permanently connected with the false bottom, because their constructive features would interfere with the manipulation of the goods in the tub; and it is only by the use of my central post that I am able at all times to have the false bottom in connection with the lifting apparatus, and to sustain the bottom at any desired height in the tub without interfering with the continued use of the tub for dyeing. The capacity of the tub above the bottom may thus be reduced to any desired degree, and a small quantity of goods manipulated with great facility. I do not, therefore, claim a false bottom in combination with a hoisting apparatus, except the former is permanently connected with the latter to operate in sustaining the false bottom at any point to which it may be lifted and to lower the same at pleasure.

Having thus fully described my invention, what I claim, and desire to secure by Letters Patent, is as follows:

1. In combination with the perforated false bottom *B*, the wooden post *R*, constructed substantially as shown and described, and connected to the perforated bottom by rod *I*, having head or nut *i* covered by a lead cap, *a*, the whole combined and operated as and for the purpose set forth.

2. In combination with a false bottom fitted to the interior of a dye-tub, a rope, hose, or similar flexible guard applied to the edge of the false bottom, substantially as and for the purpose set forth.

In testimony that I claim the foregoing I have hereunto set my hand this 30th day of April, 1880.

GEORGE YULE.
